UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TUBE-FRAME BRACKET.

Application filed December 30, 1926. Serial No. 158,066.

This invention relates to brackets forming the ends of the yarn tube frames used in Axminster carpet looms. Such brackets provide bearings for the outer ends of the 5 yarn spools and also support the chain engaging elements by which the tube frame is attached to the transporting pattern chains.

It is the object of my invention to improve the general construction of such tube frame brackets, and particularly to improve the provision for positioning a spring hook therein. A further object is to provide an improved arrangement for securing the spring hook to the bracket and for preventing 15 lateral displacement thereof.

My invention further relates to arrangements and combinations of parts which will be hereinafter described and more particularly pointed out in the appended claims.

20 A preferred form of the invention is shown in the drawings in which

Fig. 1 is a front elevation of a portion of a tube frame, partly in section, and having my improved bracket attached thereto;

25 Fig. 2 is an end elevation, looking in the direction of the arrow 2 in Fig. 1;

Fig. 3 is a front elevation, partly in section, and illustrating the manner of assembling the spring and bracket;

30 Fig. 4 is an enlarged sectional view, taken along the line 4—4 of Fig. 1; and

Fig. 5 is a view similar to Fig. 1, but showing the parts in a different position.

Referring to the drawings, I have indicated 35 a portion of a rectangular tubular member 10 which constitutes a support for the yarn tubes 11.

My improved tube frame bracket comprises 40 portions 12 and 13 secured within the tubular member 10 by screws 14. The member 12 is substantially L-shaped and the member 13 has an offset lower end portion, as indicated at 15. The upright portion of the member 12 is provided with outwardly 45 displaced bearing portions 16 (Fig. 4), engaging the member 13 and holding the members 12 and 13 in definitely spaced relation. The parts 12 and 13 are permanently secured together, however, either by rivets as indicated at 17 in Fig. 4 or by welding or 50 otherwise securing the parts together.

The member 13 is projected upwardly and has a portion 18 forming a spool bearing and

an offset portion 19 adapted to extend between the links of a transporting pattern 55 chain C. The member 13 is also provided with a slot 20 and the offset portion 19 is provided with a slot 21.

A spring hook 22, preferably of double thickness, is so formed that its lower end portion 23 may be passed downward through the slot 21 and rearward through the slot 20 and may be received in the recess 24 (Fig. 4), formed between the projections 16. The lower end 23 of the spring 22 is provided with an opening 25, and the depending portion of the member 12 is provided with a similar opening 26. A tapped hole 27 is formed in the member 13 and is aligned with the hole 26.

In assembling the parts, the spring 22 is inserted in the recess 24, and a screw 30, having a reduced cylindrical or stud 31, is inserted in the tapped hole 27. The portion 31 extends through the opening 25 in the spring and into the opening 26 in the member 12. A spring washer 32 may be placed on the reduced portion 31 and will be forced against the spring 22 to prevent displacement of the screw 30.

The lower portion 23 of the spring 22 is formed of the exact width of the slot 20 so that the spring fits snugly therein and is thus held from lateral displacement while the screw 30 at the same time prevents longitudinal displacement. The upper slot 21 is wider than the spring hook, which is thus free to swing in its upper portion.

The screw 30 is also formed of extra length and projects outward, as indicated in Fig. 5, to such a position that it may be engaged by a spring stud 35 and prevent downward movement of a clutch arm 36, if for any reason the spring hook 22 is not detached from the chain C.

A stud or stop 37 on the clutch arm 36 normally engages the spring 22 and pushes the spring back to inoperative position, as indicated in Fig. 5, whenever it is intended to disengage the tube frame from the chain.

I have thus provided a construction in which the hook 22 is very firmly retained in the tube frame bracket, and with this construction, accidental displacement of the hook is rendered practically impossible. In 105 case of breakage, however, the hook is very

easily replaced by simply removing the screw 30. The spring hook is also held from lateral displacement by the sides of the slot 20, and is free to swing at its upper portion 5 in the slot 21.

Having thus described my invention and the advantages thereof, I do not wish to be limited to the details herein disclosed otherwise than as set forth in the claims, but

10 what I claim is:—

15 1. A tube frame bracket comprising two rigid frame members, one of said members having portions up-set thereon effective to space said members apart and to provide a recess between said members and defined at the sides by said up-set portions, a spring hook having its lower end seated in said recess, and means to secure said hook in position.

20 2. A tube frame bracket comprising a rigid frame having a slot and a recess formed therein, a chain engaging hook extending through said slot and into said recess and means to secure said hook in position, portions of said hook closely engaging the sides of said slot, and said hook being held from lateral displacement by such engagement.

25 3. A tube frame bracket comprising two rigid frame members secured together in spaced relation and having a recess formed therein and open at the top only, and one of said members having a slot above said recess, a spring hook extending through said slot and into said recess, and means to secure

30 35 said hook in said recess, a portion of said spring engaging the sides of said slot and said hook being thereby held from lateral displacement.

4. A tube frame bracket comprising a rigid frame portion having upper and lower slots formed therein, and a spring hook extending through both slots and having its lower end portion firmly secured to said frame portion, said hook fitting closely against the sides of said lower slot but having substantial side clearance in said upper slot.

5. A tube frame bracket comprising a rigid frame portion having a recess formed therein and open at the top only, a spring hook seated in said recess, and a screw threaded in said frame portion and having a rearward stud projection extending through an opening in said spring hook and into an opening in said frame portion aligned therewith and firmly securing said spring hook in position.

6. A tube frame bracket comprising a rigid frame portion having a recess formed therein and open at the top only, a spring hook seated in said recess, and a screw threaded in said frame portion and having a rearward stud projection extending through an opening in said spring hook and into an opening in said frame portion aligned therewith and firmly securing said spring hook in position. said screw having an elongated threaded head portion extending outwardly to provide a lug for engagement with a portion of a clutch arm, if the tube frame does not move downward with said arm.

In testimony whereof I have hereunto affixed my signature.

ALBERT A. GORDON.
